UNITED STATES PATENT OFFICE.

HEINRICH HEINEMEYER, OF HILDESHEIM, GERMANY.

BOTTLE-VALVE.

1,068,052.

Specification of Letters Patent.

Patented July 22, 1913.

Application filed June 17, 1912. Serial No. 704,077.

To all whom it may concern:

Be it known that I, HEINRICH HEINEMEYER, a subject of the German Emperor, residing at Hildesheim, in the Province of Hanover and Empire of Germany, have invented certain new and useful Improvements in Bottle-Valves; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention has relation to improvements in non-refillable bottles, and it consists in the construction and novel combination of parts, of which it is composed, all as will be hereinafter more fully explained and particularly pointed out in the appended claim.

The annexed drawing, to which reference is made, fully illustrates my invention, in which—

Figure 1, represents a vertical sectional view of the upper portion or neck of a bottle, showing the bottle in an upright position, and Fig. 2, is also a vertical sectional view of the device, showing the neck of the bottle pointed downward, whereby said bottle is emptied of its liquid.

Referring by letter to the accompanying drawing, *a*, designates the neck of a bottle, in which is provided a recess *n* at the lower portion thereof, a dove-tailed annular recess or seat *o*, at the mouth and an annular beveled recess or shoulder *g*, a short distance from the top or mouth of said bottle, all for a purpose presently explained. Within the neck of the bottle is inserted a non-detachable receptacle or casing *b*, of peculiar construction, the same having the open outer end or mouth *p*, an annular outer rim or flange *r*, a closed bottom *e*, provided with an opening; a central partition *t*, provided with a tubular downward projection *v* and openings *f*, *f*, as well as spring holding devices *w*, and inclined plates *m*, *m*.

A valve stem *d* is arranged centrally within the casing, having a valve *k* at its lower portion and a coiled spring *h*, surrounding said stem and its end being seated in the tubular projection, of which one end thereof has its bearing upon the partition, while opposite end of said coiled spring bears upon

the valve, which latter is fast to the valve stem, the lower end *l*, of which projects downwardly, somewhat from the valve.

A ball *i*, is arranged within the recess *n* 60 and a packing *c*, is provided and seated within the dovetailed recess *o* and the same surrounds the upper portion of the casing.

Having thus described the various parts of which my device is composed, I will now 65 proceed and explain its operation.

In applying my device to the neck of a bottle, the operator simply forces the casing into the neck of the bottle until the springs *w* snap into the recess *g* thus firmly securing 70 the casing to the inside of the neck of a bottle, and preventing said casing from being withdrawn after the ball has been dropped down the neck and into the recess *n* where it remains, an annular flange comes in contact with the packing *c* thereby firmly securing the packing in position at the mouth of the bottle and this operation, is, of course, performed after the liquid has been placed

in the bottle, and by means of the valve, 80 having its spring pressure upon the bottom of the casing, the opening is tightly closed by said valve, at the same time when the bottle is in an upright or its normal position, the ball also closes the opening *x*—thus the 85 two acting as valves render the bottle air tight, thereby preventing evaporation of the liquid contained therein. In pouring the liquid from the bottle, said bottle is tilted or turned upside down when the ball will 90 immediately contact with the end *l*, of the valve stem and force the valve from the opening *s*, thereby opening said valve and permitting the liquid to flow from the bottle into the casing and through the openings 95 *f*, *f*, thence through the indirect passage formed by the plates *m*, *m*, and out mouth *p* of the casing. Should only a portion of the contents be poured from the bottle and the latter is placed in an upright position, the ball drops to its normal position in the recess *n* thus permitting the valve *k* to instantly close this valve opening.

It will be observed, from the above description when taken in connection with the annexed drawing that the inclined plates forming the indirect passage for the liquid, prevents valve from being tampered with and that when the casing is placed in the neck of the bottle, the spring holders *w*, prevent the casing from being withdrawn. And it will be further seen that it is impos-

sible to refill the bottle and when emptied of its contents, the bottle becomes worthless and at the same time it is ornamental as well as cheap to manufacture.

5   What I claim is—

In combination with the neck of a bottle provided with notches and enlarged chamber, of a casing adapted to enter the neck of the bottle and be fixed thereto, consisting
10 of a cylindrical body having an outlet, a flange, and interior inclined plates, a central perforated partition, provided with a tubular spring guide, a valve-opening in the

lower end of said casing, a valve-stem, having a valve at the lower portion thereof, a spring interposed between said valve and central partition and an operating ball, arranged within the enlarged chamber *n* and adapted to engage the lower end of the valve stem, substantially as described. 15

In testimony whereof, I affix my signature, in presence of two witnesses.

HEINRICH HEINEMEYER.
